CLAIM

The ornamental design for an arithmetic and control unit for data processing, as shown and described.

DESCRIPTION

1. Arithmetic and control unit for data processing

1.1 : Perspective view from the right side

1.2 : Perspective view from the left side

1.3 : Front

1.4 : Back

1.5 : Top

1.6 : Bottom

1.7 : Right

1.8 : Left

The parts shown in broken lines form no part of the claimed design.
